UNITED STATES PATENT OFFICE

146,909

DESIGN FOR A FRUIT SQUEEZER

Owen Luther Godwin, Lakeland, Fla.

Application February 26, 1946, Serial No. 126,915

Term of patent 14 years

(Cl. D89—1)

To all whom it may concern:

Be it known that I, Owen L. Godwin, a citizen of the United States, residing at Lakeland, in the county of Polk and State of Florida, have invented a new, original, and ornamental Design for Fruit Squeezer, of which the following is a specification, reference being had to the accompanying drawing, forming part thereof.

The single figure in the drawing is a perspective view of a fruit squeezer showing my new design.

I claim:

The ornamental design for a fruit squeezer, as shown.

OWEN LUTHER GODWIN.
